LATHER DISPENSER

Edward M. Grandinetti, 2815 Los Flores Blvd.,
Lynwood, Calif.

Filed Sept. 21, 1964, Ser. No. 81,813

Term of patent 3½ years

(Cl. D52—2)

FIG. 1

The undisclosed side of the lather dispenser is substantially the same in appearance as the side shown.

The dominant features of the design reside in the solid line portions.

I claim:

The ornamental design for a lather dispenser, substantially as shown and described.
